(57) **CLAIM**

The ornamental design for a lighting fixture, as shown and described.

DESCRIPTION

FIG. 1 is a front-side perspective view of a lighting fixture showing my new design;

FIG. 2 is a front elevational view thereof, the rear side being mirror image thereof;

FIG. 3 is a left side elevational view thereof, the right side being mirror image thereof;

FIG. 4 is a top view thereof;

FIG. 5 is a bottom view thereof; and,

FIG. 6 is a rear-side perspective view of a lighting fixture showing my new design.

The broken lines in the disclosure represent portions of the lighting fixture which form no part of the claimed design.
